UNITED STATES PATENT OFFICE.

CARL F. NAYER, OF CHICAGO, ILLINOIS.

AEROPLANE.

1,382,847.

Specification of Letters Patent. Patented June 28, 1921.

Application filed January 17, 1919. Serial No. 271,573.

To all whom it may concern:

Be it known that I, CARL F. NAYER, a citizen of the United States, residing at Chicago, in the county of Cook and State of Illinois, have invented a certain new and useful Improvement in Aeroplanes, of which the following is a full, clear, concise, and exact description, reference being had to the accompanying drawings, forming a part of this specification.

My invention relates to aeroplanes and has to do more particularly with planes of the character in which movable planes are provided preferably rotatable about a given axis but maintained in a horizontal or substantially horizontal alinement. That is, I provide a series of planes which are mounted upon rotatable spiders, the planes being adjustable so that they may be varied from horizontal to oblique angles, the planes being provided with so called feathering surfaces so that the downward movement of the plane during its rotation is effective to lift the aeroplane while the upward movement of the plane does not retard the movement of the aeroplane due to the feathering action thereof. Another feature of my invention is the provision of rotatable planes of the above character which are arranged in series and so controlled that the machine may be readily turned either while stationary or while being driven forward. Another feature of my invention is the provision of adjustable rotatable planes the position of which may be varied so as to permit a straight lift of the machine, or cause an advance or forward movement of the machine, or cause a forward travel of the machine upwardly or downwardly, or permit a straight or an inclined downward travel thereof. Other features will be pointed out more particularly in the ensuing specification and claims.

For a better understanding of my invention reference is to be had to the accompanying drawings in which—

Figure 1 is a side elevation of the preferred embodiment of my invention;

Fig. 2 is a plan view of Fig. 1;

Fig. 3 is a rear elevation of Figs. 1 and 2;

Fig. 4 is a portion of one of the planes showing more clearly the netting and the vanes carried thereby.

Fig. 5 is a section along line 5, 5 of Fig. 4 showing the feathering construction;

55

Fig. 6 is a cross section through a planetary gear connection; and

Fig. 7 is a section along the line 7, 7 of Fig. 6.

Referring now more in detail to the construction shown in the drawings I provide a platform 10 supported upon suitable wheels 11 and carrying a power plant preferably in the form of a suitable gasoline engine 12 which may be controlled from the operator's seat 13.

Mounted above this platform and power plant are series of movable planes which are supported upon a suitable framework including uprights 14, 15 and cross bars 16, 17. Supported between each pair of cross bars 16, 17 are fore and aft rotatable plane constructions each comprising a shaft 20 carrying spiders 21, 22 each having three arms as shown in Fig. 1. Each corresponding pair of arms on each spider 21, 22 has a pivotally supported plane A rotatable in the bearing 23. These planes A comprise a light metal framework made up of tubing and having a light net work 24 suitably secured to the frame and carrying a plurality of vanes or feathers in the form of strips 26 which are pivotally attached to the netting at 27, these strips being of a suitable material such as oiled silk or the like.

85 These feathers may thus be moved downwardly away from the netting as shown in Fig. 5 or upwardly against the netting by the air pressure when the plane is moving downwardly. Thus when the plane A moves upwardly in its rotation the feathering strips move away from the netting and do not retard the action of the upward movement of the aeroplane. But when the plane A is moving downwardly during its rotation, these feathering strips 26 move against the surface of the netting and thus are effective to cause a lifting action.

90 In operating the machine it is my intention to maintain these planes A in a definite horizontal or definite inclined plane during the rotation of the spider 21, as will be apparent from Fig. 1 so as to act as lifting planes only or as lifting and driving planes. To this end I provide control mechanism for 95 shifting the planes from their horizontal

position to an inclined position in either direction as indicated by the dotted lines in Fig. 1. This plane control mechanism preferably comprises an eccentric 25 which 5 is pivotally supported upon the main shaft 20 of the spider 21. This eccentric may be shifted by means of a connecting rod 27 which connects each pair of eccentrics 25 and extends through a bell crank lever 28 10 and link 29 to the operator's lever 30. These eccentrics 25 it will be understood are normally stationary, that is, they do not rotate with the shaft 20 but are held in their adjusted position. Rotatably supported upon 15 the eccentric 25 is the eccentric spider 31 each arm of which is pivotally connected to an arm 32 extending downwardly from a plane A. With this construction it will be apparent that as the plane supporting spider 20 25 is rotated the planes A will be maintained in a predetermined position relative to the axis of rotation depending upon the adjustment of the eccentric 25. These planes A are preferably staggered as will 25 appear from Fig. 1 so that the length of the aeroplane may be reduced to a minimum. Of course, this arrangement may be varied as desired.

Now in order to drive these planes A I 30 connect them by suitable gearing with a motor 12 this gearing comprising preferably (Fig. 2) a pair of bevel gears 34, 35, the gears 35 being connected by a shaft 36 which supports a bevel gear 37 in mesh with a second gear 38 connected through a universal joint 39, shaft 40, universal joint 41, and planetary gear connection B to a suitable spiral gear 42 which is connected to the motor 12. It will thus be apparent that when 35 the motor 12 is operated the connected gearing just described drives the planes A. In the above description of the driving mechanism for the planes I have simply referred to one set consisting of fore and aft planes, those positioned upon one side of 40 the machine, but it will be apparent from the drawings that the set of two planes on the other side of the machine are likewise paired and connected through a similar 45 gearing to the motor 12. The shafts 40 it will be noted revolve in opposite directions, as indicated by the arrows thereon but this, of course, is necessary with the particular 50 driving mechanism used for driving both sets of planes in the same direction.

Now in order to change the direction of 55 forward motion of the machine, I preferably vary the speed of the proper pair of planes. That is, for example if the machine is moving forward and it is desired to turn toward the left, then I either increase the speed of the right set of planes (Fig. 2) or decrease the speed of the left set of planes. Or the speed of one set may 60 be decreased and the speed of the other set 65

increased. However, it is only necessary that the speed of the two sets of planes differ so that a turning to the right or left is brought about.

To vary the speed of the sets of planes I 70 preferably provide a planetary gear transmission as shown in Figs. 6 and 7. This mechanism comprises a casing 44 having a suitable cap 45, the said casing supporting a gear 46 pinned to the shaft 47 which extends to the spiral gear 42. This gear 46 rotates freely within the casing 44 and is connected to three double pinions each comprising a small gear 48 and larger gear 49. The larger gears 49 are in turn in mesh with 75 a gear 50 pinned to the shaft 51 which extends to the universal joint 41. This gear 50 it will be noted is smaller and has fewer teeth than the gear 46. This gear 50 supports a plurality of pawls 52 which engage 80 the internal ratchet 53 carried by the gear 46, said pawls being held in engagement with the teeth of the ratchet 53, by means of the spiral springs indicated in Fig. 7. Surrounding the casing which supports this 85 gear mechanism is a brake strap 54 controlled by the brake lever 55 which when actuated holds the drum 44 against rotation so as to increase the speed of the driven shaft 51.

In the operation of this planetary gear when the driving shaft 47 is rotated in a clockwise direction (Fig. 7), the brake 54 being off, pawls 52 through their engagement with the ratchet 53 carried by shaft 51, 100 directly drive the shaft 51, both shafts 47 and 51 and the drum with its gear mechanism rotating as a unit at the same speed. Now in order to increase the speed of the driven shaft 51, the brake is applied to the drum 105 44 holding it stationary so that through the action of the gears 46, 48, 49 and 50, the shaft 51 is driven independent of the ratchet and pawl connection and because of the ratio between the gear teeth, shaft 51 rotates at a higher speed than the shaft 47. 110 Thus when the brake lever 55 of either planetary gear is operated, the corresponding planes are driven at a higher speed.

It will be noted that, due to the particular arrangement of the driving mechanism, shafts 40 (Fig. 3) revolve in opposite directions. Therefore, the ratchet teeth 53 in the planetary gears are cut in opposite directions.

In the form of my invention illustrated in Figs. 1 to 7 the rotatable planes act as both lifting and driving planes but it is to be understood that I contemplate other arrangements. For example, the rotatable planes may be arranged in sets as shown in Figs. 1 and 2, but with the axis of rotation parallel to the direction of travel and with each adjacent set of planes rotating in opposite directions and acting merely as lifting 125 130

planes. A driving propeller is then provided at the rear or front of the machine for effecting forward movement thereof. With such an arrangement the rotatable planes A 5 act merely as lifting planes and the propeller is used for driving the machine forwardly.

In the operation of the aeroplane shown in Figs. 1 to 7, the engine 12 is started and 10 the operator takes his place at the seat 1 keeping the planes A in their horizontal position. The speed of the engine is now increased until the proper lifting effect is produced and when the machine attains the 15 desired height, shifting lever 30 is moved to tilt the planes A with their front ends downwardly thus bringing about a forward movement of the aeroplane. Should the operator now desire to turn toward the left, for 20 example, right hand brake lever 55 is operated (Fig. 3) thus increasing the speed of the fore and aft planes on the right side of the machine. This will cause the machine to turn toward the left but the operator 25 may again bring about a straight forward driving by releasing the right hand brake lever 55 so as to cause the two sets of planes to rotate at the same speed. If it is desired to turn toward the right, then of 30 course the left-hand brake lever 55 is operated. Should the operator desire to stop the forward movement of the machine, control lever 30 is again moved into its neutral position thus bringing the planes into their 35 horizontal position, as indicated by the full lines in Fig. 1 and thus the forward movement of the aeroplane is stopped. Should the operator wish to move the machine backwardly, the control lever 30 is moved so as 40 to tilt the rear ends of the planes A downwardly at an angle. Or if the machine is moving forwardly and it is desired to bring about an abrupt stoppage, the planes A may be tilted from one angular position to another so as to bring about a brake effect 45 of the revolving planes.

Now supposing the aeroplane is stationary but it is desired to turn the machine without moving it forwardly or backwardly, 50 then it is only necessary to operate either one of the brake levers 55 so as to bring about a difference in speed of the two sets of planes. This will result in the turning movement of the aeroplane with practically 55 no forward or backward movement thereof.

If it is desired to lower the aeroplane, this may be done by moving it forwardly but decreasing the speed of the planes so that a gradual descent may be made. Or 60 a vertical descent may be made by adjusting the planes A horizontally and decreasing the speed to the proper point.

For the purpose of disclosing my invention I have illustrated a preferred form but 65 I contemplate applying my invention in

other ways than that shown herein and therefore I do not desire to be limited to the exact arrangement shown and described but aim to cover all that which comes within the spirit and scope of the appended claims. 70

What I claim as new and desire to secure by Letters Patent is:

1. An aeroplane including two sets of rotatable lifting planes with control means for maintaining the planes in different parallel positions throughout their rotation, and means whereby said planes are effective throughout part only of their rotation, the planes of the two sets being staggered so that the planes of one set overlap the plane of the other set during rotation of the planes. 75

2. An aeroplane including a plurality of sets of rotatable lifting planes rotating in the direction of travel of the aeroplane with control means for maintaining the planes in different parallel positions throughout their rotation so that the aeroplane will travel either forwardly or backwardly, and means whereby said planes are effective throughout only the downward movement of their 90 rotation. 85

3. An aeroplane including a plurality of sets of rotatable lifting planes with control means for maintaining the planes in parallel positions throughout their rotation, and means for changing the angle of the planes so as to act as lifting and driving planes, the planes of the two sets being staggered so that the planes of one set overlap the plane of the other set during rotation of the planes. 100

4. An aeroplane including two spiders each rotatable on a horizontal axis, a plurality of lifting planes pivotally supported one on each arm of the spiders, the planes on the two spiders being staggered so that the planes of one spider overlap the planes of the other spider during rotation, means for maintaining the planes in parallel positions throughout their rotation and means to change the angle of the planes so as to 110 cause them to act as driving means. 105

5. An aeroplane including two driving members, each member comprising a spider rotatable on a horizontal axis and in the direction of travel of the aeroplane, a plurality of lifting planes pivotally supported one on each arm of the spiders, the planes on the two spiders being staggered so that the planes of one spider overlap the planes of the other spider during rotation, means 115 for maintaining the planes in parallel positions throughout their rotation, means for simultaneously changing the angle of all the planes, and means whereby said planes are effective throughout only the downward movement of their rotation. 120

6. An aeroplane including two driving members, each member comprising a spider rotatable on a horizontal axis and in the direction of travel of the aeroplane, a plu- 130

- rality of lifting planes pivotally supported one on each arm of the spiders, the planes on the two spiders being staggered so that the planes of one spider overlap the planes of the other spider during rotation, means for maintaining the planes in parallel positions throughout their rotation, means for simultaneously changing the angle of all the planes, means whereby said planes are effective throughout only the downward movement of their rotation, and said means for changing the angle of the planes being adapted to change the angle of said planes so as to act as driving planes also.
15. An aeroplane including fore and aft spiders rotatable in the direction of travel of the aeroplane on horizontal axes, lifting planes pivotally supported one on each spider arm, the planes of one spider overlapping the planes of the other spider during rotation, means for simultaneously driving the planes in the direction of travel of the aeroplane, and means for maintaining the planes in a definite position relative to the horizontal and parallel to each other, throughout their rotation.
8. An aeroplane including fore and aft spiders rotatable on a horizontal axis, lifting planes pivotally supported one on each spider arm, said spider arms being staggered so that the fore and aft planes alternately extend between the opposite planes, means for simultaneously driving the planes, and means for maintaining the planes in a position approximately parallel to the horizontal throughout their rotation.
9. An aeroplane including two sets of fore and aft spiders rotatable on a horizontal axis in the direction of travel of the aeroplane, lifting planes pivotally supported one on each spider arm, means for driving the planes, and means for varying the relative speed of the sets of planes.
10. An aeroplane including two sets of fore and aft spiders rotatable on a horizontal axis in the direction of travel of the aeroplane, lifting planes pivotally supported one on each spider arm, means for driving the planes, and means including an interposed planetary gear transmission for varying the relative speed of the sets of planes.
- ed one on each spider arm, means for driving the planes, and means including an interposed planetary gear transmission for varying the relative speed of the sets of planes.
11. An aeroplane including two sets of fore and aft spiders rotatable on a horizontal axis in the direction of travel of the aeroplane, lifting planes pivotally supported one on each spider arm, means for driving the planes, means including an interposed planetary gear transmission for varying the relative speed of the sets of planes, and means for varying the position of the planes so as to act as driving and lifting planes.
12. A driving member for aeroplanes comprising a frame having a netting thereon, pivotally attached vanes or feathers mounted directly on said netting which overlap and lie against the netting during the driving movement of the plane but fall away from the netting during non-driving movement thereof, an arm supporting the frame and means to maintain the frame at any desired angle with the horizontal regardless of the angular position of the arm.
13. An aeroplane including a rotatable spider, a plane pivotally supported on each arm of the spider, an eccentric surrounding the axis of rotation of the spider, and a connection from the eccentric to each plane whereby the planes are held in successive definite positions parallel to each other.
14. An aeroplane including a rotatable spider, a plane pivotally supported on each arm of the spider, an eccentric surrounding the axis of rotation of the spider, a connection from the eccentric to each plane whereby the planes are held in successive definite positions parallel to each other, and means for adjusting the eccentric to vary the relation of the planes to the axis of rotation.
- In witness whereof, I hereunto subscribe my name this 27th day of November, A. D. 1918.

CARL F. NAYER.
